UNITED STATES PATENT OFFICE.

GEORGE E. DAVIS, OF DES MOINES, IOWA, ASSIGNOR OF FORTY-NINE PER CENT TO
WILLIAM OREM, OF CHICAGO, ILLINOIS.

STOPPER AND SPRINKLER CAP FOR BOTTLES AND THE LIKE.

Application filed May 10, 1926. Serial No. 107,971.

The object of my invention is to provide a stopper and sprinkler cap for bottles and the like of simple, durable and comparatively inexpensive construction.

5 More particularly it is my object to provide a stopper and sprinkler cap wherein the contents of the bottle may be discharged therefrom when the stopper stem is raised upwardly or withdrawn from a cork mounted in the bottle having a central opening.

Still a further object is to provide a device including a cork mounted in a bottle neck having a central opening and a stem adapted to extend into the opening in the 15 cork and having a guide thereon whereby the stem may be withdrawn from the opening and the guide will retain the stem in proper position so that downward movement of the stem will again cause it to be inserted 20 in the opening in the cork.

Still a further object is to provide a stopper stem mounted in guides or bearings and having a slot or opening extending lengthwise of the stem and terminating short 25 of its bottom end so that when the stem is not in engagement with a cork opening, the contents of the bottle may be poured or discharged through the slot or opening in the stem and when the lower end of the 30 stem is in the opening in the cork the bottle will be sealed.

Still a further object is to provide a non-removable stopper limited in its downward movement by the cork in the bottle neck 35 and to its upward movement by a cap adapted to extend over and surround the upper end of the bottle itself.

Still a further object is to provide a stopper stem which is not removable and 40 whether in open or closed position will always be connected with the bottle.

With these and other objects in view, my invention consists in the construction, arrangement and combination of the various 45 parts of my invention, whereby the objects contemplated are attained, as hereinafter more fully set forth, pointed out in my claims, and illustrated in the accompanying drawings, in which:

50 Figure 1, is a side view of a bottle with my improved stopper and sprinkler top shown thereon in section.

Figure 2, is a central sectional view taken on line 2-2 of Figure 1.

Figure 3, is a perspective view of the 55 stopper stem showing the discharged slot therein.

Figure 4, is a sectional view through a stopper stem having a discharged opening centrally located therein, and 60

Figure 5, shows a sectional view of a slightly different form of cork.

In the accompanying drawings I have used the reference numeral 10 to indicate generally a bottle having a neck 11 and an 65 outturned upper lip or flange 12.

Mounted within the neck 11 of the bottle 10 is a cork element 13 having a central opening 14. The opening 14 is in communication with an enlarged opening 15 also 70 formed in the cork element 13. The opening 15 serves as a guide for the stopper stem as will hereinafter be more fully described.

Formed over the upper end of the neck 11 and around the lip 12 is a cap 16 formed 75 of soft pliable metal wherein it may be bent to conform to the neck and lip of the bottle 10.

The cap 16 is formed with a central opening 17 defined by the upturned flange 18. 80 The opening 17 serves as a bearing and guide for the stopper stem.

Received within the openings 14, 15 and 85 17 is a stopper stem element A. The stopper stem element A includes a body portion 19 of the same diameter as the opening 17 and the body portion 19 is slidable within the opening 17.

The lower end of the stopper element A is contracted and forms a pin 20 of the same 90 diameter as the opening 14. A guide and stop element 21 is also formed on the stopper stem A and the guide and stopper element is of the same diameter as the opening 15.

The guide element 21 is capable of movement up and down within the opening 15 when the stop element A is raised or lowered.

The pin 20 seals the opening 14 and thereby prevents any discharge from the contents of the bottle 10. A longitudinally arranged slot 22 is formed in the stopper stem A above the guide element 21 and it is through this slot 22 that the contents of the bottle 105 may be discharged when the stopper stem is in its raised position as shown in Figure 2 of the drawings.

As shown in the drawings the slot 22 also extends through the guide element 21. The upper end of the stopper stem A is grooved as at 23 so as to define a head 24 upon the upper end of the stem A.

The guide element 21 and the opening 17 serve to center and guide the stem A when it is raised or lowered. The stem A frictionally engages with the upturned flange 10 or collar 18 on the cap so that when the stem A is in raised position it will remain in such position and when in lowered position will remain in such position unless manually moved.

15 The guide element always insures the pin 20 to register with the opening 14 when it is desired to insert the pin 20 in the opening 14.

In the practical use of my improved stopper and sprinkler top it is necessary to raise 20 the stopper stem A to the position shown in Figure 2 and thereafter by turning the bottle upside down the contents from the bottle may be discharged.

25 In the discharge of the contents it first passes through the opening 14 and then into the opening 15. The slot 22 permits part of the contents from the opening 15 to pass therethrough and onto the head 24.

The head 24 tends to spread and sprinkle 30 the discharged contents from the bottle. When the stem is moved to its down position that is as shown in Figure 1 of the drawings, the stem 20 entirely seals the opening 14 and serves as a stopper for the bottle.

35 In Figure 4 of the drawings I have shown in place of the slot 22, a centrally arranged opening 25 which terminates short of the lower end of the stem A and through this opening the contents of the bottle are discharged in the same manner as through the slot 22.

In Figure 5 I have shown the bottle neck 40 as formed with a stop 26 for limiting the amount of downward movement of the cork 13. The cork 13 in this case is formed with a central opening 14.

The pin 20 of the stem A extends into the opening 14 and seals the bottle. The guide element 21 which is formed upon the stem A 50 in this case is of the same diameter as the neck opening in the neck of the bottle and the neck of the bottle serves as a guide for the stem A.

In the form shown in Figure 5, the guide 55 element 21 and the opening 17 in the cap 16 serve as the two guides for positioning the post 20 relative to the opening 14.

In the practical use of the stopper and sprinkler top shown in Figure 5, I find that 60 the bottle neck above the cork 13 serves in the same manner as does the opening 15 formed in the cork itself.

When the stem A is in raised position the 65 contents of the bottle when upside down passes through the opening 14 into the neck

portion of the bottle normally above the cork 13 and thereafter the contents may be discharged through the slot 22 or other opening formed in the stem A.

It will be noted that in the assembly of 70 my stopper and sprinkler top it is necessary to first insert the cork 13 within the bottle neck and thereafter place the stem A in position.

The cap 16 is then slipped over the upper 75 end of the stem A and thereafter crimped around the lip 12 of the bottle 10.

After the device is assembled the downward movement of the guide element 21 and the stem itself is limited by engagement with 80 the cork 13 and its upward movement is limited by engagement with the cap 16.

The advantage of my stopper and sprinkler top consists in the arrangement wherein 85 the contents may be discharged by simply pulling the stopper upwardly. The stopper is not removable.

The slot 22 or opening 25 are the only 90 means whereby the contents of the bottle may be discharged and it would be impossible to refill the bottle through slot 22 or opening 25 and my sprinkler top and stopper serve for providing a non-refillable bottle.

Some changes may be made in the arrangement and construction of the various parts 95 of my device, without departing from the essential features and purposes of my invention, and it is my intention to cover by my claims any modified forms of structure or use of mechanical equivalents, which may be 100 reasonably included within their scope.

I claim as my invention.

1. In combination with a neck of a bottle, a stopper and sprinkler cap comprising a member mounted in the neck having a central opening, a stem in the neck of the bottle having a part adapted to be received in said opening for closing it, a cap covering the upper edge of the bottle and spaced from the opening in said member, said stem extending through said cap, a guide element formed on said stem adapted to travel between said member and said cap when raised and lowered, said stem having a passageway formed therein above the part adapted to be received in said opening whereby the contents may be discharged through said cap when said last part is not received in said opening.

2. In combination with a neck of a bottle, 120 a stopper and sprinkler cap comprising a member mounted in the neck having two central openings therein of different diameters, a cap over the upper edge of the bottle, a movable stem mounted in said cap having parts adapted to fit in the two different openings whereby the bottle is sealed against discharge of its contents, said stem being capable of movement to position where one of its parts is withdrawn from its respective 125 130

opening for allowing the contents of the bottle to be discharged therethrough.

3. In combination with a neck of a bottle, a stopper and sprinkler cap comprising a member mounted in the neck having two central openings therein of different diameters, a cap over the upper edge of the bottle, a movable stem mounted in said cap having parts adapted to fit in the two openings, one of said parts serving as a guide element and the other of said parts serving as a stopper element by filling its respective opening when the stopper is moved to one position.

4. In combination with a neck of a bottle, a stopper and sprinkler cap comprising a member mounted in the neck having two central openings therein of different diameters, a cap over the upper edge of the bottle, a movable stem mounted in said cap having a part adapted to be guided in one of said openings and another part adapted to fit in the other of said openings, said stem having

a passageway therein above the part adapted to fit into said second opening.

5. A stopper and sprinkler cap comprising a member mounted in the neck of a bottle, an opening therein, a portion of said opening being reduced whereby a shoulder is formed in the opening, a cap covering the bottle and retaining said member in the neck thereof, an opening in said cap, a stem adapted to extend through the opening in said cap and into the reduced portion of the opening in said member, a flange on said stem adapted to be guided by the large portion of the opening in said member and adapted for travel between said shoulder and said cap whereby the stem is withdrawn from the reduced portion of said opening when said flange is moved to position adjacent the cap and means for allowing the contents of the bottle to be discharged past the flange and through the opening in said cap.

GEORGE E. DAVIS.
